PARACHUTE HARNESS

Harold G. Rogers, Buffalo, N. Y., assignor to
Irving Air Chute Company, Inc., Buffalo, N. Y.,
a corporation

Application March 30, 1937, Serial No. 133,883

6 Claims. (Cl. 244—151)

This invention relates to improvements in
parachute harness constructions.

The primary object of this invention is the pro-
vision of an improved parachute harness of the
5 single point release type having an improved
construction by means of which a quick con-
nector pack may be attached thereto at the front
of the wearer in a safe, convenient and easy ac-
cessible relation.

10 Other objects and advantages of the inven-
tion will be apparent during the course of the
following detailed description.

In the accompanying drawings, forming a part
15 of this specification, and wherein for the purpose
of illustration is shown a preferred construction
of the improved harness,

Figure 1 is a perspective view showing the im-
proved harness upon a wearer with a quick con-
nector pack attached thereto.

20 Figure 2 is a similar view with the quick con-
nector pack removed.

Figure 3 is a perspective view of the harness
showing its detailed construction.

25 Figure 4 is a cross sectional view showing the
manner in which couplings are affixed upon the
harness and pack so that they may be easily con-
nected together without fumbling.

30 Figures 5 and 6 are cross sectional views taken
through details of the harness substantially on
the respective lines shown in Figure 3 of the
drawings.

In the drawings, wherein similar reference
35 characters designate corresponding parts
throughout the several views, the letter A may
generally designate the improved harness which
is adapted for use with a quick connector pack
B, such as the soft pack type shown in a co-
pending application Serial No. 134,109, filed
March 31, 1937. The harness is generally of the
40 type set forth in an application Serial No. 94,470,
filed August 5, 1935, except that the harness of
the latter application has been adapted for use
with a quick connector pack having permanent
coupling connections on the front portion of the
45 harness and in a relation upon the harness which
will permit of the safe and expeditious applica-
tion of the pack upon the harness.

Generally the harness A includes a supporting
50 sling 30 of double webbing stitched together and
providing a seat portion 31 and vertical riser
webs 32 and 33 which extend from the seat portion
and are adapted to be placed upwardly at the
sides and towards the front of the wearer and
55 over the shoulders at 34 and 35; the double
webbing continuing rearwardly as back straps

36 and 37 cross each other at a point 38. At
the point 38 the double webbing ends in slip
loops at the crossing point 38, which hold the
back straps 36 and 37 in a crossed relation per-
mitting of limited play. The straps 36 and 37 8
terminate in permanent connections 40 and 41
with the riser webs 33 and 32 respectively. As
will be noted from Figures 3 and 5 of the draw-
ings each of the straps 36 and 37 adjacent to its
permanent connection with the riser web has 10
an adjustment. This adjustment, as is shown
for the strap 36 in Figure 5, consists in providing
a short tab loop 42 which is permanently stitched,
as at 43 to the riser web 33 (see Figure 3). It
has a connector ring 44 thereon through which 15
the doubled end of the strap 36 is threaded.
This strap 36 at its extreme end has a three bar
adapter 45 which is adjustably connected on the
intermediate portion of the strap 36. By sliding
the adapter 45 along the strap 36 the back strap 20
may be adjusted in length to suit the stature of
the wearer. The construction is identical for
both the back straps 36 and 37.

Breast straps 50 and 51 are permanently con-
nected at points 52 and 53 with the upper ends 25
of the riser webs 32 and 33 respectively adjacent
to the shoulder portions 34 and 35 thereof. They
extend therefrom in a downwardly slightly con-
vergent relation and slidably extend through
suitable tunnels 54 and 55 respectively in the 30
riser webs 32 and 33 at a location above the hips
of the wearer, and above the fixed connections
40 and 41 of the back straps. The end of each
strap 50 and 51 at the sides and back beyond
the slide tunnels 54 and 55 is extended horizon- 35
tally across the small of the back of a wearer
and each end of each strap 50 and 51, as thus
extended across the back of a wearer, is pro-
vided with a three-bar adapter 57, best shown in
Figure 6 of the drawings. These adapters for 40
each of the straps 50 and 51 extended is ad-
justably threaded on the other strap so as to
provide a rear horizontal back strap adjustment
which may suit the girth of the wearer so as not
to displace the riser webs and breast straps upon 45
the wearer.

It will thus be noted that the straps 50 and 51
form not only breast straps, but also a horizontal
back strap. On the breast strap loops the straps
50 and 51 are provided with slidably threaded 50
coupling or fastener parts 60 and 61 for releas-
able connection with a quick release fitting C.

The quick release fitting C may be of the nature
set forth in co-pending application Serial No.
94,470, or of the type shown in U. S. Patents Nos. 55

1,842,611 or 1,899,656. The connector C may be releasable from all the fittings, but it is preferred to make at least one of the fittings, such as the fitting 61 with a permanent connection to the quick release fitting C. The latter operates as set forth in the above patents and need not be further detailed here.

5 Leg straps 70 and 71 are formed of double layers of stitched webbing, connected at approximately the central location 72^a on the seat strap 31 of the suspension sling. These leg straps 70 and 71 are of greater length than leg straps of quick release harnesses heretofore provided. They are adjustable, as to length, by 10 means of adapters 72 of the three-bar variety. These adapters 72 are on the extreme ends of the doubled leg straps which are doubled upon themselves to furnish adjustment loops. At the 15 ends of these adjustment loops coupling fittings 76 and 77 of the same nature as the fittings 60 and 61 are provided for releasable connection with the quick release fitting C. Each leg strap extends, as shown in Figures 1, 2 and 3 of the drawings, from the crotch of the wearer, underneath 20 the adjacent side riser strap, at the hip of the wearer, and then across the front of the riser strap for connection to the quick release fitting C.

The quick connector pack B is of the type 25 described in my application Serial No. 134,109, filed March 31, 1937, preferably of the soft pack variety in which the pack floats away after the rip cord is pulled and the parachute has opened. It is provided upon the exterior of the container 30 with definitely spaced and located couplings 80, preferably of the snap fastener variety, which when the parachute pack is unopened, are in a fixed location upon the pack by means of a construction set forth in my above identified application Serial No. 134,109, filed March 31, 1937, and also shown in application Serial No. 9,670, filed March 6, 1935. This construction need not be enlarged upon except to say that the pack B has a container 82 and the parachute packed 35 therein is provided with suspension webs 83 terminating in the snap fasteners 80. The latter extend exteriorly of the pack and are permanently located exteriorly on the container by means of a wire pin 84 on the suspension strap 83, which extends through a suitable stud 85 on the snap fastener, as shown in Figure 4. This definitely and fixedly locates the snap fastener 80 exteriorly on the pack, when the pack is closed 40 for quick attachment to the complementary coupling part located on the harness, without necessity of fumbling.

The harness A is provided with an improved coupling arrangement which consists of a ring 90 permanently fixed and located upon each side 45 riser web 32 and 33 of the harness just above the tunnel through which the breast strap slides, and preferably above the center of gravity of the wearer. These coupling rings 90 are sloped upwardly at an acute angle to the riser web portion 50 thereabove, so as to facilitate the application of the snap fastener thereto. As a safeguard, the portion of the riser web 32 and 33 above the coupling ring 90 is stiffened and rendered almost rigid by means of a double portion of webbing 93 located between the layers of the riser web, as 55 shown in Figures 3 and 4 of the drawings, which is sewed by a multiple stitching arrangement to the webs of the riser straps of the harness. The complementary connector ring 90 has closely spaced bar portions 95 and 96 through which the

65 webbing is threaded, and to which the webbing is stitched in the relation shown in Figure 4, so that the coupling ring 90 will hold the acute angled relation with the stiffened portion of the riser web to which it is attached.

70 Various changes in the shape, size, and arrangement of parts of the harness may be made to the form of invention herein shown and described, without departing from the spirit of the invention or the scope of the claims.

75 I claim:

1. In a parachute harness the combination of a suspension sling arrangement including side riser webs, other body attaching straps connected with said sling arrangement, a parachute pack having coupling parts connected therewith for releasable coupling to the parachute harness, and complementary coupling rings permanently and fixedly connected upon the riser webs of the harness in 80 outstanding relation therefrom at the normal front of the wearer and sloped upwardly to facilitate attachment of the coupling parts of the pack thereto.

2. In a parachute harness the combination of a suspension sling arrangement including side riser webs, other body attaching straps connected with said sling arrangement, a parachute pack having coupling parts connected therewith for releasable coupling to the parachute harness, and complementary coupling members permanently and 85 fixedly connected upon the riser webs of the harness at the normal front of the wearer and acutely sloped upwardly to facilitate attachment of the coupling parts of the pack thereto, the coupling parts of the pack being of the snap fastener variety and the coupling parts of the riser webs being of the loop type.

3. In a parachute harness the combination of a suspension sling arrangement including side riser webs, other body attaching straps connected with 90 said sling arrangement, a parachute pack having coupling parts connected therewith for releasable coupling to the parachute harness, complementary coupling members permanently and fixedly connected upon the riser webs of the harness at 95 the normal front of the wearer and acutely sloped upwardly to facilitate attachment of the coupling parts of the pack thereto, the coupling parts of the pack being of the snap fastener variety and the coupling parts of the riser webs 100 being of the loop type, the respective riser webs immediately above the coupling loops connected therewith being rigidly stiffened.

4. In a parachute harness the combination of a suspension sling, including a seat portion, side 105 riser webs and back straps serving as extensions of said riser webs and disposed in crossing relation at the back and having permanent connection with the opposite riser webs at about the normal waist of a wearer, leg straps connected 110 with the seat straps, means for adjusting the length of the said back straps, breast straps connected with the riser webs, and a quick release fitting for releasably connecting the leg straps and breast straps together.

5. In a parachute harness the combination of a U-shaped suspension sling including a seat portion and side riser webs, said side riser webs extending upwardly to provide shoulder portions and thence continuing directly in crossing relation at the normal back of a wearer to provide back straps having connection with the side riser webs at about the waist of the wearer, breast straps, leg straps, a single point release fitting for 120 releasably connecting all of the breast and leg 125

straps together at the front of a wearer, and parachute pack attaching couplings on the side riser webs below the shoulders in definitely position load suspension relation thereat.

6. In a parachute harness the combination of a U-shaped suspension sling including a seat portion and side riser webs, said side riser webs extending upwardly to provide shoulder portions and thence continuing directly in crossing relation at the normal back of a wearer to provide back straps having connection with the side riser webs at about the waist of the wearer, breast

straps, leg straps, a single point release fitting for releasably connecting all of the breast and leg straps together at the front of a wearer, and parachute pack attaching couplings on the side riser webs below the shoulders in definitely position load suspension relation thereat, said couplings being positioned in outstanding non-wobbling position so that a pack may be directly connected thereto without the necessity of manual fumbling with said couplings. 5 10

HAROLD G. ROGERS.
